CLAIM

The ornamental design for a lamp for a vehicle, as shown and described.

DESCRIPTION

FIG. 1 is a perspective view of a lamp for a vehicle wherein the surface shading is intended to show that the front cover of the lamp is transparent;
FIG. 2 is a front view thereof;
FIG. 3 is a rear view thereof;
FIG. 4 is a right side view thereof; a left side view being a mirror view of the right side view;
FIG. 5 is a top plan view thereof;
FIG. 6 is a bottom plan view thereof; and,
FIG. 7 is a cross-sectional view taken along line 7-7 in FIG. 4 thereof.

The broken lines showing on the drawing disclosure are for illustrative purposes only and form no part of the claimed design.
